UNITED STATES PATENT OFFICE.

THEODORE CHANOCK, OF CHICAGO, ILLINOIS.

DESIGN FOR A SPINDLE FOR LIGHTING FIXTURES.

Application filed February 3, 1926. Serial No. 16,380. Term of patent 3½ years.

To all whom it may concern:

Be it known that I, THEODORE CHANOCK, a citizen of the United States, residing at Chicago, in the county of Cook and State of Illinois, have invented a new, original, and ornamental Design for a Spindle for Lighting Fixtures, of which the following specification, reference being had to the accompanying drawings, forms a part thereof.

Figure 1 is a view in elevation of a spindle for lighting fixtures embodying my invention; and

Figure 2 is an end view of the spindle.

I claim:

The ornamental design for a spindle for lighting fixtures, substantially as shown.

THEODORE CHANOCK.
